UNITED STATES PATENT OFFICE.

WILLIAM S. GREY, OF DES MOINES, IOWA.

SEAT-SUPPORTING DEVICE.

No. 888,799.

Specification of Letters Patent.

Patented May 26, 1908.

Application filed June 20, 1907. Serial No. 379,886.

To all whom it may concern:

Be it known that I, WILLIAM S. GREY, a citizen of the United States, residing at Des Moines, in the county of Polk and State of Iowa, have invented a certain new and useful Seat-Supporting Device, of which the following is a specification.

My invention relates to the class of seats usually employed in circuses, grand stands, etc., which may be quickly and easily taken apart for purposes of transportation, and which may be quickly and easily set up when desired. In seats of this kind, it is desirable to have a main bank of seats having an approximate seating capacity which it is desired to use under normal conditions, and in some instances it is desirable to provide an extra bank of seats, which may be quickly and easily placed in position in front of the main bank, to provide an additional number of seats, in cases where a greatly increased seating capacity is desired.

My object is to provide an improved seat supporting device, of simple, durable and inexpensive construction, by means of which an auxiliary bank of seats may be quickly and easily attached to the main bank, without need for driving stakes, or erecting supports other than the stringers themselves that support the seats proper.

My invention consists in the construction, arrangement and combination of the various parts of the device, whereby the objects contemplated are attained, as hereinafter more fully set forth, pointed out in my claims, and illustrated in the accompanying drawings, in which—

Figure 1 shows a side elevation of a main bank of seats, and an auxiliary bank of seats attached thereto, and embodying my invention. Fig. 2 shows a rear elevation of one of the main and auxiliary stringers, with portions of seats thereon, and a trestle for supporting the upper end of the main stringer. Fig. 3 shows an enlarged detail perspective view of a portion of a main stringer, and a portion of an auxiliary stringer connected by means of my improved connecting device. Fig. 4 shows a similar view with the auxiliary stringer slightly detached from the main stringer, and illustrating a modified form of my invention. Fig. 5 shows an inverted plan view of the end of the auxiliary stringer of the form shown in Fig. 4, and Fig. 6 shows a view like Fig. 3, illustrating another modification.

Referring to the accompanying drawings, I

have used the reference numeral 10 to indicate the main stringer. This stringer is supported throughout its length with a series of brackets 11 on its top, the surface of such shape that when the stringer is supported in the position shown in Fig. 1, the tops of the brackets will be substantially horizontal, so that seat boards 12 may be placed thereon. For supporting the rear end of the stringer 10, I have provided a trestle 13, of the ordinary kind, and for supporting the front end of the stringer, I drive a post or stake 14 into the ground, to be engaged by the end of the stringer. Near the lower end of the stringer, 70 is a bracket for forming a seat support, which bracket is made of a single piece of iron rod, having its body portion 15 arranged at the same angle as the tops of the brackets 11, and having its upper end inclined downwardly, and inserted in the stringer at 16, and its lower end inclined downwardly at 17, and inserted in the stringer. This bracket is the same in all of the modified forms of my invention. 80

The auxiliary seat support comprises a stringer 18, designed to have its upper end supported upon the lower portion of the stringer 10, and to be held against lateral movement relative to the stringer 10, by means of the bracket 15. On top of the stringer 18 is a series of wooden brackets 19, to support the seat boards 20, these brackets being so arranged that when the stringers 18 are in the position shown in Fig. 1, the seat 90 boards will be substantially horizontal.

In the preferred form of my invention as illustrated in Figs. 1, 4 and 5, I provide for holding the stringers 18 against downward movement relative to the stringer 10 as follows: Mounted on the stringer 10, adjacent to the bracket 15 is a plate 21, having an opening through it to receive a pin 22, having a tapered or rounded head 23, projecting above the plate. The body of the pin is inserted in an opening in the stringer 10. The adjacent end of the stringer 18 is provided on its under surface with a plate 24, having a longitudinal slot 25 therein, designed to receive the upper end of the pin 23. In order 100 to prevent lateral movement of the stringer 18 relative to the stringer 10, I form in the upper end of the stringer 18, a slot 26, and in order to strengthen and reinforce the parts, I place a metal plate 27 on top of the stringer 110 18, provided with wings 28, to overlap the sides of the stringer, and provided with the

slot 29 in its top, to stand in line with the slot 26. This plate is secured by bolts or screws to the stringer 18. In connecting the parts together, I first place the end of the stringer 18 with the upright portion 17 of the bracket 15 resting in the slots 26 and 29. In order to do this, the forward end of the stringer 18 must be elevated to a substantially horizontal position, then the forward end of the stringer is lowered so that the head 23 of the pin 22 will enter the slot 25, and the forward end of the stringer may then be lowered to rest upon the ground. By this means, all lateral movement of the stringer 18 is prevented, and all longitudinal movement of the stringer 18 is prevented by the pin 22 in the slot 25, and it is not necessary to provide any stakes, posts or other fastening devices for the forward ends of the stringer 18.

20 In the modified form shown in Fig. 3, I have substituted for the pin and slot structure described, a device consisting of a plate 30, mounted on top of the stringer 10, and having a rounded shoulder 31 at its central portion, extending across the top of the stringer 10, and on the under surface of the stringer 18 I have placed a plate 32 having its upper end curved to form a cylinder 33, which is designed to rest in the rounded shoulder 31, and thus prevent the downward movement of the stringer 18 relative to the stringer 10.

In the modified form shown in Fig. 6, I have provided a plate 34 in the upper end of the stringer 18, which plate is formed with a hook 35 having a slot therein designed to receive the upright portion 17 of the bracket 15, said slot being so arranged as to prevent lateral movement of the stringer 18 on the stringer 10, the outer end of the hook being in engagement with the upright portion 17 in such manner as to prevent downward movement of the stringer 18 relative to the stringer 10.

45 In practical use, I first set up a number of the main stringers 10, as shown in Figs. 1 and 2, and place thereon the seat boards 12. In this way a complete bank of seats is formed which may be used without the auxiliary 50 bank of seats, if desired. In the event that the main bank of seats proves insufficient, and it is desirable to quickly add additional seats, I then place the stringers 18 on the brackets of the main stringer 10 in the manner before described. The forward ends of the stringers 19 are permitted to rest upon the ground, and are held against longitudi-

nal movement by the fastening devices at the rear ends thereof so that additional stakes or posts are unnecessary, then the seat boards 60 20 are placed upon the brackets of the auxiliary stringers, and an additional bank of seats is thus readily and quickly provided

Having thus described my invention, what I claim and desire to secure by Letters Patent 65 of the United States, therefor, is—

1. In a device of the class described, the combination of a main stringer, a seat board supporting bracket thereon, comprising a metal rod with its ends secured to the top of 70 the main stringer, and its body portion designed to receive a seat supporting board, an auxiliary stringer designed to rest upon the top of the main stringer, and formed with a slot in its end to receive the forward end of 75 said bracket for preventing lateral movement, and means for preventing the auxiliary stringer from moving downwardly on the main stringer.

2. In a device of the class described, the 80 combination of a main stringer, a seat board supporting bracket thereon, comprising a metal rod with its ends inserted in the top of the main stringer, and its body portion designed to receive a seat supporting board, an auxiliary stringer designed to rest upon the top of the main stringer, and formed with a slot in its end to receive the forward end of 85 said bracket, and means for preventing the auxiliary stringer from moving downwardly 90 on the main stringer, said means comprising a pin fixed to the main stringer, and a slotted plate to receive said pin, fixed to the auxiliary stringer.

3. In a device of the class described, the 95 combination of a main stringer, a seat supporting bracket thereon comprising a rod with its ends inserted in the top of the main stringer, and its body portion shaped to support a seat board, a plate fixed to the main stringer, adjacent to said bracket, a pin passed through said plate and inserted in the stringer, and having a pointed end projecting above said plate, and an auxiliary stringer having a slotted plate fixed to its under surface to receive said pin, and also having a metal plate on its top with wings overlapping its sides, said top plate and the upper end of the stringer being formed with a slot to receive 100 105 the lower upright portion of said bracket.
